[57] ABSTRACT

External air and a charge of augmented air from an air augmenter or booster are directed through passages defined by a series of spaced horizontally oriented guide plates. Fuel picked up by the uppermost stream of air is driven over a series of ribs where it is successively impinged and atomized at different levels by the incoming streams of air. The air fuel mixture, now substantially atomized, if forced through a series of downstream guide plates and further atomized with the aid of plural downstream ribs.

A special fuel injection mechanism in conjunction with the relay valve operates to quickly cut-off the supply of fuel when there is a temporary lack of demand for the fuel in order to minimize air pollution and smog.

FIG. 2.

FIG. 3.

VEHICLE FUEL INJECTOR

BACKGROUND OF THE INVENTION

This invention generally relates to carburetors and more specifically relates to vehicle carburetors capable of thoroughly atomizing fuel and cutting-off unnecessary charges of fuel in order to reduce smog and air pollutants.

This invention is primarily an improvement over the carburetor atomization structure disclosed in U.S. Pat. No. 3,559,963 to Cedarholm in which fuel droplets temporarily trapped in corrugations formed in the mixing chamber wall are blasted by entering air streams to assist in atomizing the fuel.

This invention also relates to other Cedarholm patents i.e. U.S. Pat. No. 2,653,804, U.S. Pat. No. 2,762,615 and U.S. Pat. No. 2,984,467.

SUMMARY OF THE INVENTION

Briefly stated the present invention is a fuel injection and vehicle carburetor that coact to appreciably improve atomization of fuel in order to increase combustion efficiency.

In its broader aspects the invention has an atomization housing defining a mixing chamber for accepting and mixing charges of fuel and air. An air inlet structure defines an air inlet aligned in communication with the mixing chamber to constitute a continuous flow passageway for air and subsequently air and fuel mixtures. An upper section of the atomization housing is equipped with a series of inwardly projecting fins that are spaced from one another to define pockets that form thin fuel films. A throttle valve located in the continuous flow passageway regulates the flow of external air into the mixing chamber in the usual manner. A fuel injector has a metering valve which projects into the mixing chamber. An arm interlinks the metering valve and throttle valve to synchronize proportions of fuel and external air being admitted into the mixing chamber. The purpose of the fins is to partially break up and atomize the fuel and the pockets hold fuel fins where the fuel is blasted and further atomized by an incoming stream of air from the air inlet structure.

Preferably another set of fins is formed by a lower atomization section of the atomization housing. These fins also project inwardly into the mixing chamber and are spaced from one another to define lower pockets to temporarily collect fuel films that escape from the upper pockets. The lower fins serve to sequentially break up and further atomize the fuel while the lower pockets hold fuel for being blasted and impinged by the stream of air and air fuel mixture, the combined effects of the dual set of fins and pockets being to aid in thoroughly atomizing fuel for enhancing combustion.

Upper blades extend across the mixing chamber and are connected to internal walls of the atomization housing. The upper blades are spaced to define upper passages generally aligned with the air inlet and are oriented to direct separate streams of air towards at least some of the pockets. Lower blades are also coupled to the atomization housing and extend across the mixing chamber. The lower blades are sloped relative to the upper blades and spaced from one another to define lower passages oriented to direct separate streams of air generally toward the lower pockets.

A pressure responsive pneumatic relay physically separated from the atomization housing may be used to provide important advantages. Conduit means connect the relay valve and atomization housing. A spring biased shuttle is responsively coupled to the relay valve through the conduit means so that when vehicle deceleration occurs the shuttle automatically shifts the fuel injector to a location where communication is blocked between the metering valve and fuel injector. A fuel

10 container secured to the shuttle defines a fuel chamber surrounding an upper portion of the fuel injector. A flexible diaphragm interconnects the fuel injector and atomization housing and a vacuum chamber is defined in part by the fuel container, fuel injector, atomization housing and flexible diaphragm. The flexible dia-

15 phragm includes an outer relatively thick annular band connected in leakproof relationship with a portion of the atomization housing, an inner relatively thick annular band formed with gripping ribs secured in leakproof relationship with the fuel container, and, a relatively thin intermediate section arranged to flex upwardly when pressure in the vacuum chamber exceeds a pre-determined level.

20 25 The shuttle is a generally upstanding tube whose upper end is fixed to the fuel container for simultaneous movement therewith. The fuel injector includes an axially movable plunger located at least partially within the shuttle and the plunger and shuttle coact to define at least one flow channel for routing fuel from the fuel container to the metering valve. Preferably the plunger is formed with at least three radially outwardly connecting ribs that terminate adjacent the shuttle to define at least three flow channels.

30 35 An air augmenter is provided for supplying additional air to the mixing chamber. The air augmenter has a duct extending through the air inlet and terminates in a tubular section which is coaxially aligned with the air inlet structure.

40 45 BRIEF DESCRIPTION OF THE DRAWINGS

The numerous benefits and unique aspects of the present invention will be fully understood when the following detailed description is studied in conjunction with the drawings in which:

FIG. 1 is a side elevational, fragmentary, longitudinally sectional view of a vehicle fuel injector system constructed in accordance with this invention and connected with a pressure responsive fuel cut-off valve;

50 FIG. 2 is a top plan sectional view taken along line 2-2 of FIG. 1; and,

FIG. 3 is a rear elevational partially sectional view taken from the right side of the carburetor as shown in FIG. 1, showing certain horizontally aligned blades for splitting incoming air into separate layered air streams.

DETAILED DESCRIPTION OF THE PREFERRED EMBODIMENT

60 FIG. 1 shows a vehicle carburetor and fuel injector assembly 10 constructed to finely atomize fuel charges prior to combustion in order to significantly minimize smog problems. Assembly 10 has an outer shell constituted by a fuel injector and atomizer housing 11 which includes an upper atomization section 12 and a lower atomization section 13. A base portion 14 of lower atomization section 13 is sized for securement over the

intake manifold of a vehicle internal combustion engine (not shown).

Extending laterally from housing 11 is an air inlet structure 15 that has an open outer end 16 through which external or ambient air A_1 may enter. The inner end 17 is fixed to or formed with housing 11. The internal geometry defined in part by housing 11 and in part by the inner end 17 of air inlet structure 15 constitutes a mixing chamber 18 having a narrow throat portion 18 A.

Coupled to air inlet structure 15 is an air augmenter or booster 20 through which air A_2 driven by an external pump or compressor (not shown) is forced into air inlet structure 15. Air augmenter 20 includes an elbow shaped pipe 21 having a laterally projecting section 22 relative to the axis of air inlet structure 15 and a bent tubular section 23 that is coaxially aligned with the axis of air inlet structure 15. Mounted within the exit port of tubular section 23 is a cone 24 whose apex 25 is aimed in an upstream direction and which terminates in a diverging or flaring end 26. The cone 24 and surrounding exit of tubular section 23 define a nozzle or annular restricted passage 28. Air A_1 flowing through the air inlet 15 and air A_2 flowing through the air augmenter 20 converge and become commingled to form a mixed air charge A_3 which is routed towards the mixing chamber 18.

Journalized within a bearing carried by housing 11 is a rotatable control shaft 30 suitably connected through a conventional linkage to the vehicle accelerator pedal (not shown). Depression of the accelerator pedal by the vehicle driver causes shaft 30 to rotate in a direction indicated by directional arrow R which in turn causes a butterfly type throttle valve 31 to rotate from a closed position indicated by the solid lines to a progressively more opened position indicated by the dot dash line 30 A. As the throttle valve 31 becomes increasingly opened then greater charges mixed of air A_3 are admitted into the mixing chamber 18. A section of the throttle valve 31 below the axis of shaft 30 mounts a bowed projecting, interlinking arm 32 terminating in a cam 33.

A generally vertically aligned elongated needle-type metering valve 34 is formed in its periphery with a longitudinally extending fuel injection channel 35 which is gradually enlarged from its upper end over and a sufficient distance and constitute desired variable flow characteristics. The base 36 of metering valve 34 operates as a cam follower and is constantly engaged by cam 33. As shaft 30 is rotated in direction R, cam 33 will lift metering valve 34 exposing an increasingly greater zone of fuel injection channel 35 so that the incoming charges of air A_3 and fuel will be synchronized in a predetermined ratio.

The upper atomization section 12 has an upwardly extending annular neck 40 formed with a radially outwardly extending dish-shaped flange 41. Flange 41 terminates in a circular shaped beaded portion or lip 42. The inner section of neck 40 includes an upstanding annular wall 43 fixed to an internal tubular bushing 44.

Positioned internally of bushing 44 is a stationary intermediate tube 45 which defines a bore and has a depending lower section defining a deflector plate 46. Deflector plate 46 projects into and is located on the relatively upstream side of mixing chamber 18 and operates to assist in splashing or deflecting fuel in a desired

direction as shall be more fully explained. The upper end of intermediate tube 45 constitutes a bearing seat 47.

Situated within the bore of intermediate tube 45 is an axially movable shuttle 49 whose upper end 50 is located adjacent bearing seat 47 constitutes a stop flange. The shuttle lower end 51 is internally threaded. Positioned generally within the upper zone of chamber 18 is a valve seat 52 having an externally threaded upper section 53 that is threadably interengaged with shuttle lower end 51 so that the two components can be moved upwardly or downwardly together. Valve seat 52 has a central bore 54 which serves as a guideway for metering valve 34, and, has a series of flow passages 55 through which fuel from channel 35 may pass into mixing chamber 18.

Under normal conditions stop flange 50 rests upon bearing seat 47 so that no gap G is present. As shall be more fully explained during deceleration conditions 20 when it is desirable to immediately cut-off the fuel supply, shuttle 49 and valve seat 52 will be urged upwardly so fuel injection channel 35 will be covered and under such circumstances a gap G will be created.

Referring to both FIGS. 1 and 2 the bore of shuttle 25 49 occupies a plunger rod 60 of solid cross section. Plural longitudinally extending flow channels 61 are defined in part by multiple radially outwardly projecting ribs 62. The upper end of plunger rod 60 terminates in an apex or cone tip 63 and the lower end 64 of plunger rod 60 contacts metering valve 34.

The fuel injector includes a fuel container 65 with a cylindrically shaped top plate 66 and a disc shaped bottom plate 67 welded or otherwise secured in fluid tight relationship with plate 66. The uppermost tip 68 of 35 shuttle 49 is inserted through a central opening of plate 67 so that stop flange 50 and tip 68 can tightly engage, either directly or indirectly, opposing faces of plate 67. Plate 67 has an outer depending skirt 69 that is generally surrounded by a diaphragm 70.

Diaphragm 70 includes an intermediate thin flexible pressure sensitive strip joined to an end band 72 and an inner end band 73. Outer band 72 is generally thick and durable and shaped for making leakproof snap-fitting engagement on the periphery of the lip 42 of annular neck 40. The inner band is also generally thick and durable and has a series of gripping ribs or seals 74 that are sized to make tight leakproof engagement against depending skirt 69. The generally confined space defined in part by annular neck 40, diaphragm 70 and plate 67 constitutes a vacuum chamber 78. When the pressure within the vacuum chamber 78 is increased due to deceleration the fuel container 65 moves upwardly under force from a coiled compressed spring 79 and causes the diaphragm 70 to flex. Shuttle 49 is therefore automatically caused to move upwardly to block off further supply of fuel to the mixing chamber 18. The effect of this action is to reduce fuel flow and thus maintain the correct amount of fuel relative to the throttle opening.

Confined within the fuel container 65 is spring 79 that mounts a lower retaining disc 80 in contact with the cone tip 63 of plunger rod 60, and, mounts an upper retaining disc 81 arranged in contact with a downwardly extending cone tip 83. Cone tip 83 is part of an adjustment screw 82 threadably engaged within a fitting mounted within fuel container 65. The coil spring 79 immersed in fuel F floats between the two

cone tips while being supported between the two retaining discs. A nipple 84 admits fuel into the fuel chamber defined by fuel container 65.

A pressure port 86 is formed in annular neck 40 to be in communication with vacuum chamber 78. In a similar manner a pressure port 87 is formed in the lower atomization section 13 of housing 11 to be in communication with mixing chamber 18.

For heating efficiency purposes a water jacket 100 surrounds a portion of mixing chamber 18.

The other components of this invention will be described in connection with the explanation of how the invention operates.

OPERATION

Keeping the above construction in mind it can be understood how some of the disadvantages of carburetor systems are overcome. Shown schematically to one side of and physically separated from the vehicle fuel injector 10 is a pressure responsive pneumatic relay valve 88 which operates as a fuel cut-off control. The particular structure and inner mechanism of relay valve 88 is not a part of this invention and preferably it is the same as the fuel cut-off control shown and described in much detail in U.S. Pat. No. 3,559,963 to Cedarholm. Relay valve 88 has a conventional filter 89 through which interior valve locations are exposed to atmospheric pressure. A flexible tube 90 capable of being coupled to pressure port 86 operates to place vacuum chamber 78 in communication with relay valve 88. In a similar manner flexible tube 91 capable of being coupled to pressure port 87 serves to place mixing chamber 18 in fluid communication with relay valve 88.

Extending substantially entirely across the upper portion of mixing chamber 18 is a series of flat parallel guide blades 92. Guide blades 92 are parallel, equally spaced in a tier and oriented so as to define a plurality of passages 93 aligned generally parallel with the axis of air inlet 15. Incoming air A_3 is split by the guide blades 92 into streams which follow generally straight paths past metering valve 34 to points downstream. Fuel injected into the upper passage is picked up and carried downstream by the associated stream of air. The fuel is driven against a series of inwardly projecting fins 94 formed on the internal wall of the upper atomization section 12.

Fins 94 define a series of pockets 95 into which some streams of air traveling through passages 93 are directed in order to impinge upon temporarily formed thin films of fuel. With the fuel substantially atomized the air fuel mixture is routed downstream through a series of sloped downstream guide blades 96 that define passages 97. Additional downstream fins 98 define pockets 99 in the lower atomization section 13. Fins 98 and pockets 99 function like fins 94 and pockets 95.

As the air fuel mixture leaves the uppermost passage of passages 93 it crosses the entering air current of the next lower passage to thereby result in constant collision between the air and fuel mixture. A violent turbulence is constantly taking place to assure atomization. As the fuel and air mixture passes through the narrow throat 18 A it is optimurnly atomized and ready for delivery to the vehicle engine.

From the foregoing it will be evident that the present invention provides a vehicle fuel injector in which all of the various advantages are fully realized.

What is claimed is:

1. A fuel injector and vehicle carburetor assembly for atomizing fuel, comprising:

- a. an atomization housing defining a mixing chamber for accepting and mixing charges of air and fuel;
  - b. air inlet structure having an air inlet in communication with the mixing chamber to aid in defining a continuous flow passageway;
  - c. a throttle valve positioned in the continuous flow passageway to regulate flow of external air from the air inlet into the mixing chamber;
  - d. a fuel injector coupled to the atomization housing;
  - e. a metering valve connected to the fuel injector and projecting into the mixing chamber;
  - f. an arm interconnecting the metering valve and throttle valve and arranged to synchronize the proportions of fuel and external air admitted into the mixing chamber;
  - g. parallel and spaced upper blades coupled to the atomization housing and extending entirely across the mixing chamber to slice incoming external air into separate horizontal streams of air;
  - h. plural upper fins defined by the atomization housing and projecting into the mixing chamber at a location downstream of the upper blades, the upper fins being spaced from one another to define upper pockets for temporarily collecting fuel films - wherein, the upper fins serve to partially break up and atomize the fuel while the upper pockets hold fuel films for being blasted and further atomized by the streams of air issuing from the spaces between the upper blades; and,
  - i. plural lower fins defined by the atomization housing and projecting into the mixing chamber, the lower fins being spaced from one another to define lower pockets to temporarily collect fuel films that escape from the upper pockets - wherein, the lower fins serve to sequentially break up and further atomize fuel while the lower pockets hold fuel for being further blasted and impinged by streams of air and fuel-air mixture,
- wherein, the combined effects of the blades, upper fins, upper pockets, lower fins, and lower pockets aid in thoroughly atomizing fuel to improve combustion.

2. The structure according to claim 1, including: lower blades coupled to the atomization housing and extending across the mixing chamber, the lower blades being sloped relative to the upper blades and spaced from one another to define lower passages oriented to direct separate streams of air generally toward the lower pockets.

3. The structure according to claim 1, including: a pressure responsive pneumatic relay valve physically separated from the atomization housing; conduit means connecting the relay valve and atomization housing; a spring biased shuttle responsively coupled to the relay valve through the conduit means so that when vehicle deceleration occurs the shuttle automatically shifts the fuel injector to a location where communication is blocked between the metering valve and fuel injector; a fuel container secured to the shuttle and defining a fuel chamber surrounding an upper portion of the fuel injector;

a flexible diaphragm interconnecting the fuel injector and atomization housing; and,
a vacuum chamber defined in part by the fuel container, fuel injector, atomization housing, and flexible diaphragm.

4. The structure according to claim 3, wherein the flexible diaphragm includes:

an outer relatively thick annular band connected in leakproof relationship with a portion of the atomization housing;
an inner relatively thick annular band formed with gripping ribs secured in leakproof relationship with the fuel container; and,
a relatively thin intermediate section arranged to flex upwardly when pressure in the vacuum chamber exceeds a predetermined level. 15

5. The structure according to claim 3, wherein:
the shuttle is a generally upstanding tube whose upper end is fixed to the fuel container for simultaneous movement therewith; and,
the fuel injector includes an axially movable plunger located at least partially within the shuttle, the plunger and shuttle coacting to define at least one flow channel for routing fuel from the fuel container to the metering valve. 20

6. The structure according to claim 5, wherein; the plunger is formed with at least three radially outwardly projecting ribs which terminate adjacent the shuttle to define at least three flow channels.

7. The structure according to claim 5, including:
a coil spring located within the fuel container that interconnects the plunger and upper portion of the fuel container.

8. The structure according to claim 1, including:
an air booster for supplying additional air to the mixing chamber.

9. The structure according to claim 8, wherein;
the air booster includes a duct extending through the air inlet and terminates in a tubular section coaxially aligned with the air inlet structure.

10. The structure according to claim 9, wherein the air booster includes:

a cone positioned within the down stream end of the tubular section to define a restricted annular passageway so that air forced through the air booster can be commingled with external air flowing through the air inlet structure prior to the combined air masses being directed to the mixing chamber.
